(57) **CLAIM**

The ornamental design for a waist trainer belt, as shown and described.

DESCRIPTION

FIG. 1 is a front, right and top perspective view of a waist trainer belt, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled 9 in FIG. 1 comprising straps.

The dot-dash lines in FIGS. 1 and 9 are for the purpose of depicting the boundary lines of the enlarged view and form no part of the claimed design.
